CLAIM

The ornamental design for a filter insert/removal tool, as shown and described.

DESCRIPTION

FIG. 1 is a perspective view of the filter insert/removal tool; FIG. 2 is a front view of the filter insert/removal tool; FIG. 3 is a back view of the filter insert/removal tool; FIG. 4 is a left-side view of the filter insert/removal tool; FIG. 5 is a right-side view of the filter insert/removal tool; FIG. 6 is a top side view of the filter insert/removal tool; FIG. 7 is a bottom side view of the filter insert/removal tool; and,

FIG. 8 is a cross-sectional view of FIG. 6 of the filter insert/removal tool.

Surface shading in the figures is provided solely to indicate contour. All other portions of my filter insert/removal tool not shown in the figures or otherwise described in the specification form no part of the claimed design.
